UNITED STATES PATENT OFFICE.

BERTRAM COLMAN CANDEE AND WILLIAM NICKLIS PIERCE, OF BUFFALO, NEW YORK, ASSIGNORS TO PIERCE FUSE CORPORATION, OF BUFFALO, NEW YORK, A CORPORATION OF NEW YORK.

FUSE.

1,400,938.

Specification of Letters Patent. Patented Dec. 20, 1921.

Application filed October 16, 1917, Serial No. 196,941. Renewed May 20, 1920. Serial No. 382,928.

To all whom it may concern:

Be it known that we, BERTRAM C. CANDEE and WILLIAM N. PIERCE, citizens of the United States, residing at Buffalo, in the 5 county of Erie and State of New York, have invented new and useful Improvements in Fuses, of which the following is a specification.

This invention relates to a fuse of that 10 type in which the fuse-link is renewable when the same burns or blows out, thereby enabling the casing, terminals and other permanent parts of the fuse which receive the fuse-link and coöperate with the fuse-block, 15 to be used over and over again.

It is the object of this invention to devise a fuse of this character which is very simple in construction, capable of being produced at low cost and also permits of conveniently 20 and quickly renewing the fuse as well as preventing the use of the fuse in a fuse-block unless the parts are shifted relatively to each other into such a position that the fuse-link is completely inclosed and thereby 25 insuring the safety of the persons handling the fuse and also guarding against the danger of fire adjacent to the fuse when the same blows out.

In the accompanying drawings:

30 Figure 1 is a vertical longitudinal section of a fuse embodying the invention. Fig. 2 is a similar section taken on line 2—2, Fig. 1. Fig. 3 is an end view of the fuse. Figs. 4 and 5 are transverse sections taken on the 35 correspondingly numbered lines in Fig. 1. Fig. 6 is a detached side elevation of the inner tubular section of the fuse. Fig. 7 is a fragmentary side view of one end of the outer tubular section of the fuse casing. Fig. 40 8 is a fragmentary side view of the outer casing section showing a modified form of the means for arresting the movement of the same in the direction in which the fuse casing is closed.

45 Similar characters of reference indicate corresponding parts throughout the several views.

The inclosing casing of the fuse comprises inner and outer tubular sections 1, 2, which 50 fit one into the other and are adapted to slide lengthwise relatively to one another in the manner of a telescope for the purpose of opening or closing the fuse for introducing the fuse-link into the space within

the casing. These casing sections are constructed of an electric insulating material such as vulcanite and are preferably of the same length or substantially so when the sections are telescoped one within the other. The outer casing section is provided at one 55 end and on diametrically opposite sides thereof with longitudinal notches 3, 3, extending inwardly from the edge thereof, but the opposite end of this casing section is unnotched. The inner casing section is provided on one side with a longitudinal filling 60 opening 4. This opening should preferably be equal in length to the fuse link 5 to permit of introducing the latter sidewise through this opening and into the inner casing section. This opening may be uncovered for this purpose by sliding the outer 65 casing section lengthwise away from this opening.

6, 7, represent two outer end caps which 70 are preferably cup-shaped and constructed of sheet metal and which in the normal or closed position of the casing are arranged at opposite ends of the two casing sections with their concave sides facing inwardly. 75 One of these caps, for instance 6, is secured to the outer casing section by suitably indenting the cylindrical portion or flange thereof, as shown at 8, so that these indentations engage with the outer casing section 80 and act as spurs or anchors which prevent this cap from pulling off the respective casing section. The other outer end cap 7 fits over the opposite end of the outer casing section with a sliding fit, so that these parts 85 can be separated lengthwise from each other and also pushed together for opening or closing the casing. Each of these outer end caps is provided with a central terminal 90 opening 9 which preferably is constructed 95 in the form of a slot extending transversely across the transverse plate of this cap, and each of these outer end caps is also provided with vent openings 10, two of which are 100 preferably formed on the plate of the cap on opposite sides of the central terminal opening, as shown in Figs. 2 and 3.

11 represents two inner end caps preferably of sheet metal which are arranged in opposite ends of the inner casing section 105 and each of which is constructed in the form of a cup which has its concave side facing outwardly and engages its flange

against the bore of the inner casing section while its plate is arranged at a distance from the plate of the adjacent outer cap, so that in the closed position of the two casing sections, a space or chamber 12 is formed between each pair of inner and outer caps. Each of the inner caps is provided in the central part of its plate with a terminal opening 13 and on opposite sides of this 10 terminal opening with vent openings 14, as best shown in Figs. 2, 4 and 5. Within each of the spaces between a pair of end caps and preferably extending across the vent openings of the inner cap, is arranged a screen of woven wire 15 which operates to prevent any flashes of fire from passing from the central part of the casing which contains the fuse-link through the vent openings 14, 10 of the inner and outer caps, 15 but will permit the escape of any gases from the casing when the fuse blows out. Internal pressure within the casing is by this means avoided as would be liable to occur if no vent were provided, while at the same 20 time guarding against setting fire to anything in the immediate vicinity of the fuse.

Within each of the spaces 12 between a pair of end caps is arranged a metal bridge which may be variously constructed, but in 30 the preferred form comprises a cross piece 16, two attaching lugs 17, 17, arranged on opposite sides of the cross piece and a longitudinal terminal lug 40 projecting from the central part of the cross piece through 35 the central opening 13 of the respective inner end cap and into the adjacent part of the compartment within the inclosing casing. One of these bridges, for instance, the one arranged at the left hand end of Figs. 1 40 and 2, is connected only with the adjacent end of the inner casing section and the respective inner end cap by means of coupling screws 18 passing through corresponding openings formed in the inner casing and the 45 flange on this end cap while their threaded inner ends engage with threaded openings in the side lugs 17 of the respective bridge while their heads are countersunk in the outer side of the inner casing section. The 50 other bridge is connected with both inner and outer caps at the respective end of the inner casing section, this being preferably accomplished by means of coupling screws 19 passing transversely through corresponding 55 openings in the flanges of the respective end caps and engaging their threaded inner ends with internally threaded openings in the side lugs of the respective bridge while their heads bear against the outer side of 60 the flange of the respective outer cap. In the assembled position of the parts and when the fuse casing is completely closed, the notched end of the outer casing section bears against the inner side of the transverse plate 65 of the end cap 7, this being possible by

reason of the shanks of the fastening screws 19 receiving the notches 3 on the adjacent end of the outer casing section, thereby aiding in limiting or stopping the closing movement of the casing sections relatively to each other, and also preventing the notched end of the outer casing section from being twisted circumferentially with reference to the inner section.

20, 21 represent two metal terminals 75 whereby the fuse is connected with the terminals of a fuse-block. Each of these fuse terminals is provided with a comparatively wide and flat outer part which engages with the terminal of the fuse block and is arranged in the terminal slot of one of the outer caps and a narrow inner part which extends across the space between the companion inner and outer caps and through the central terminal opening of the respective 80 inner cap and into the adjacent part of the space within the casing. In the space between each pair of caps the companion terminal and bridge are connected, preferably, by means of a rivet 22, as shown in Figs. 1, 85 2 and 4. The inner parts of each terminal and the adjacent terminal lug of each bridge are detachably connected with one end of the fuse-link, this being preferably accomplished by means of a clamping screw 23 90 having its threaded shank engaging with an internally-threaded opening formed in the inner end of the respective terminal and the adjacent part of the terminal lug of the respective bridge and provided at one end 95 100 with a head between which and the terminal one end of the fuse-link is adapted to be clamped. Complete withdrawal of the clamping screw 23 is prevented by providing its threaded end with a stop 25 which is preferably formed by means of a bur or flange at this end of this screw. For convenience in attaching the fuse-link to the inner ends of the terminals, one end of the same is provided with a longitudinal slot or 105 notch 26 which extends to the end of the link and at its opposite end with a lateral slot 27 which extends transversely to one side thereof. By this means the longitudinally-slotted end of the link may be first engaged 110 with its respective clamping screw and then the fuse-link may be swung on this screw as a fulcrum for engaging its transversely slotted end with the other clamping screw, after which both of these screws may be 115 tightened for securely holding the fuse-link 120 in place.

Lengthwise movement of the two casing sections relatively to each other for separating them and opening the casing is limited 125 so as to prevent complete separation of these parts, which means are preferably so organized that they also aid in preventing these two casing sections from rotating one relative to the other and thereby always retain 130

these casing sections in their proper position relatively to each other. This stopping and guiding device preferably comprises a longitudinal slot 28 formed in the inner casing section opposite to its filling opening 4 and providing the inner side of the outer casing section with a stopping and guiding pin or lug 29 which engages with this slot. Upon pulling the two casing sections apart, 10 the stop pin 29 of the outer casing section engages with the rear end of the slot 28 in the inner casing section and limits the movement of these parts relatively to each other at a point at which the outer ends of the 15 terminals 20, 21 are still arranged within the terminal slots of the outer caps, thereby preventing disarrangement of these parts and permitting the same to be again quickly pushed inwardly one over the other for closing the inclosing casing of the fuse after a 20 new fuse link has been introduced into the casing and secured to the terminals.

Inasmuch as it is impossible to attach the outer ends of the terminals of this fuse to 25 the terminals of a fuse-block without completely closing the casing sections, the danger of fire or injury to the operator is positively prevented inasmuch as the fuse is incapable of use until the parts have been 30 stored to their proper and safe position.

Instead of providing the outer casing section with notches for the reception of the coupling screws 19, this section may be divided so as to form a body portion 30 and 35 an end ring 31 confined within the end cap by the screws 19 which engage with co-operating notches 32, 33 in the opposing edges of the body 30 and ring 31, as shown in Fig. 8.

Owing to the simplicity of the several parts which comprise this fuse, the ease with which the same can be manufactured and the low cost at which the same can be assembled, this fuse as a whole is less expensive than 45 those heretofore in use. Furthermore, this fuse can be very quickly opened and closed and refilled with a new fuse-link in the event that this becomes necessary without requiring any special tools for this purpose 50 and without the need of any skilled help.

We claim as our invention:

1. A fuse provided with a casing having inner and outer tubular sections of insulating material which are slidably lengthwise 55 relatively to one another, said inner section having an opening in its side for the introduction of a fuse link into the casing, in combination with outer end caps of metal one secured to one end of the outer casing 60 section and the other secured to the opposite end of the inner casing section, and each of said outer end caps being provided with an opening, inner end caps of metal secured to the opposite ends of the inner casing section and each provided with an opening and

separated from the adjacent outer end cap by an intervening space, a terminal arranged in said openings of the corresponding end caps and having an inner end portion arranged within the casing and an outer end portion arranged outside of the casing, a bridge arranged in the space between each pair of inner and outer caps and secured to the respective inner cap and terminal and provided with a part projecting through the 70 respective inner cap, and means for attaching a fuse link to the inner ends of said terminals.

2. A fuse provided with a casing having inner and outer tubular sections of insulating material which are slidably lengthwise relatively to one another, said inner section having an opening in its side for the introduction of a fuse link into the casing, in combination with outer end caps of metal, 80 one secured to one end of the outer casing section and the other secured to the opposite end of the inner casing section, and each of said outer end caps being provided with an opening, inner end caps of metal secured to 85 the opposite ends of the inner casing section and each provided with an opening and separated from the adjacent outer end cap by an intervening space, a terminal arranged in said openings of the corresponding end caps and having an inner end portion arranged within the casing and an outer end portion arranged outside of the casing, a bridge arranged in the space between each 90 pair of inner and outer caps and secured to the respective inner cap and terminal and provided with a part projecting through the respective inner cap, and means for attaching a fuse link to the inner ends of said terminals.

3. A fuse comprising a casing having inner and outer tubular sections of insulating material which are slidably lengthwise relatively to one another, said inner section having an opening in its side for the introduction of a fuse link into the casing, outer end caps of metal, one secured to one end of the outer casing section and the other secured to the opposite end of the inner casing section, and each of said outer end caps being provided with a terminal opening and a vent opening, inner end caps of metal secured to opposite ends of the inner casing section and each provided with a terminal opening and a vent opening, and a terminal arranged in 100 the terminal openings of each pair of adjacent end caps.

4. A fuse comprising a casing having inner and outer tubular sections of insulating material which are slidably lengthwise relatively to one another, said inner section having an opening in its side for the introduction of a fuse link into the casing, outer end caps of metal, one secured to one end of the outer casing section and the other secured 110 115 120 125 130

to the opposite end of the inner casing section and each of said outer end caps being provided with a terminal opening and a vent opening, inner end caps of metal secured to 5 opposite ends of the inner casing section and each provided with a terminal opening and a vent opening, a terminal arranged in the terminal openings of each pair of adjacent 10 end caps, and a screen arranged between the end caps of each pair.

5. A fuse comprising inner and outer tubular casing sections of insulating material which are slidable lengthwise relatively to 15 each other, said outer casing section being provided at one end with a notch while its opposite end is unnotched, outer end caps of metal one of which is secured to the unnotched end of the outer casing section while the other is slidable lengthwise on the opposite 20 site notched end of the same, inner end caps of metal arranged at the opposite ends of

said inner casing section, a screw arranged in the notch of said outer casing section and connecting the outer and inner caps on the respective ends of the casing sections, and 25 terminals arranged on said caps and adapted to be connected within the casing by a fuse link.

6. A fuse comprising inner and outer tubular casing sections of insulating material 30 which are slidable lengthwise on each other and the inner section being provided with an opening for the introduction of a fuse into the casing and a longitudinal stop and guide slot, a stop and guide projection arranged on 35 the outer casing section and projecting into said slot, and terminals mounted on opposite ends of said inner casing section and adapted to be connected within the casing by a fuse link.

BERTRAM COLMAN CANDEE.
